THEODORE B. LEWIS, OF NEW YORK, N. Y., ASSIGNOR TO SECURITY SEAL & LOCK CORP. OF NEW YORK, N. Y., A CORPORATION OF NEW YORK

UNLOCKABLE SAFETY LOCK

Application filed January 18, 1927. Serial No. 161,748.

This invention relates to unlockable safety-locks for containers and particularly for containers such as envelopes which are made of paper or like material.

5 Money and documents are often stored or placed in the mails inside of containers and it is of prime importance to know whether the contents of a container have been accessible to anyone during the time that it was 10 out of a principal's hands. Consequently, several fastening devices or locks have been devised for use on envelopes or other containers and which are intended to be free from unauthorized tampering and unlockable without such alteration or destruction of 15 the lock as would make known the fact that some one had meddled with the container or with its contents. It is known that many of 20 the so-called safety-locks are capable of performing their useful functions only as against the ordinary ability of man and that a person skilled in the construction and operation of such locks and having criminal 25 cunning with the assistance of wires or of thin blades of steel can open such locks by causing the disengagement of the locking members. A person having particular skill 30 in practicing such trickery can perform the illicit operation without leaving any marks or in any way giving indication that the lock has been unlocked.

It is among the purposes of my invention to render impossible the practices set forth and to produce an unlockable safety-lock 35 which cannot be circumvented without leaving telltale indications. To this end I provide, as one section of the safety-lock, an enveloping member or sheath of such shape as to make it possible to place its locking 40 element well within the sheath and away from the opening of the sheath. The sheath is so conformed as to snugly accommodate the blade element of a second section of the safety-lock, the construction of the sheath 45 section being characterized by its thinness and by the fact that the under surface of the sheath directly contacts the paper or flexible material of the envelope so that the additional effort of the paper assists in maintaining 50 the outline or edges of the spring or lock-

ing element of the sheath within the sheath and out of range of any tool or blade no matter how introduced.

Further and other objects are set forth hereinafter together with details of the invention which are described and illustrated. The drawings illustrate one embodiment of the invention, in which:

Fig. 1 is a plan view of the safety-lock.

Fig. 2 is a view from the under side of the 60 safety-lock illustrated in Fig. 1.

Fig. 3 is a section on line 3—3 of Fig. 1 with the sheath section member in engagement with a sheet of paper or flexible material. 65

Fig. 4 is a side elevation of the safety-lock.

Referring now particularly to the drawings, the safety-lock comprises two individual sections; a sheath section 10 and a blade element section 11, both of which are illustrated in an engaged relation, and in a disengaged relation in Fig. 4. As disclosed, the sheath section 10 is made up of a single piece of sheet metal having two major portions, 70

an upper lap 12 and an under lap 13 connected together at one edge of the section by a fold 14. For ordinary purposes, this fold may be along either of the two side edges of the sheath section 10 but I have found that it is desirable to have the fold at the rear 75

edge of the sheath section as illustrated. The upper lap 12 has a raised central portion 15 which has a clear or open space of a height preferably a little greater than the thickness of the sheet metal used. The under surface 80

of the portion of the upper lap outside of the area of the central portion 15 is maintained in contact with the opposite portion of the upper surface of the lower lap by a plurality of lugs 16, 17 which extend from the upper lap 12 and are adapted to be bent over the under surface of the under lap 13 in the manner illustrated in Fig. 2. Lugs 16 comprise 85

a pair of lugs near to the rear edge 14 of the sheath section, and lugs 17 comprise a pair of lugs having such length and position as to perform desired functions which will be referred to hereinafter. 90

A spring locking element 18 is cut out of the under lap 13 in such a manner as to be dis- 100

posed opposite the raised central portion 15 of the upper lap 12, the spring locking element having its free and engaging end extending toward, and near to, the rear end 14 of the sheath section. This spring locking element is biased upwardly, as illustrated in Fig. 3, and the locking end may come into contact with the under surface of the upper lap 12. In order to assist in the spring action 10 of locking element 18 as well as to maintain all portions thereof above the plane of the under surface of the under lap 13, lugs 17 are extended over a portion of the edges of the locking element. The spring portion of locking element 18 preferably starts just to the rear of the rear edges of these lugs. Accordingly, there cannot be any edge of the locking element above which a blade of metal could be inserted, no matter how thin the 20 blade might be.

The blade element 19 of the blade element section 11 is intended to enter the clear or open space formed by the raised central portion 15 opposite the forward edge 20 of the under lap 13. The position of this forward edge 20 is illustrated, in the present embodiment, as finishing to the rear of the forward edge 21 of the upper lap 12 and, if the two laps are finished off at approximately the 30 same lengths, it would not be necessarily desirable to provide an opening or slot 22 in the upper lap 12. This slot is desirable, however, for it permits the forward edge 21 of the upper lap 12 to be offset so as to lie below the blade element 19 when the two sections are 35 in engagement, Fig. 3. This construction provides a snug locking relation which contributes to the value of the safety-lock in that the only opening or entrance to the clear or 40 open space below the raised portion 15 is of a minimum size and has close-fitting edges.

In addition to the advantage just referred to, the open space is designed so as to have the long measurement extending from the slot 22 45 to the rear edge of the sheath section 10. Such a design enables the locking elements of the two sections to be placed well out of reach and away from the forward end of the sheath section. The blade element 19 has a lip 23 50 extending below the under surface of the blade element. It is desirable that the forward edge of this lip be at a distance, from shoulders 24, 24 of the blade element section 11, which is but slightly greater than the distance 55 of the rear locking end of the spring locking element 18 from the slot 22. Under these conditions, when the blade element 19 is inserted within the clear space of the sheath section 10, the spring locking element 18 will engage and slip above the lip 23 only 60 when the blade element is pushed home. Any attempts to draw the two sections apart would only serve to cause the end of the locking element 18 to enter at greater length through 65 the hole which lip 23 forms. The extent of

this movement is limited and would amount to approximately the distance of shoulders 24, 24 from the slot 22 as illustrated in Fig. 1.

The under surface of the under lap 13 is intended to come into contact with the flexible material or paper of the envelope with which the safety-lock is to be used and this is another feature which is characteristic of the present invention. When the sheath section 10 is mounted in position all of the prongs 25, extending from the sheath section and provided for this purpose, are bent over to engage the paper and at the same time the under surface of the sheath section is firmly pressed against the other side of the paper. The result of this operation is that a tight fit exists between the sheath section and the paper with the effect that the relative expansibility or reaction of the paper below the spring locking element 18 (as illustrated at 26) tends to give further assistance in maintaining locking element 18 raised, thereby securing the locked relation with lip 23 when the sections are together. In securing the sheath section to the paper, the paper may be scored, if desired, in such a manner as to permit the lugs 16, 17, to more easily work into the paper.

The various prongs 25 are so proportioned and placed as to prevent any possible tampering with the safety-lock by attempting to get at the locking element from a position just above the surface of the paper.

In one aspect, the paper to which the sheath element is secured forms a backing for this section, and this feature contributes to the production of a safety-lock which is made up of a minimum number of layers of sheet metal and is devoid of wasted space. A safety-lock having these assets is very desirable because of the space saved and the lessening of the number of probabilities of engagement with other envelopes, containers or mail matter.

The design of the blade 19 of the blade element section 11 already has been disclosed. The head 27 preferably has a rounded smooth contour 28 exposing no angular edges which could engage other articles. The three prongs 29 are triangularly placed and when they are turned over against the under surface of the paper the edges 28 of the head are brought into close contact with the paper. Prongs 30 contribute added strength to the fastening and all of the prongs serve in one manner or another in assisting to prevent the introduction of a thin tool beneath the blade element section 11 for the purpose of affecting the locking element 18. This locking element, it will be remembered, is disposed as far away from the slot 22 as is possible practically. The outwardly extending shoulders 24, 24 further protect the approach to the slot 22.

While the form of safety-lock herein shown and described is admirably adapted to fulfill the objects primarily stated, it is to be under-

stood that it is not intended to confine the invention to the one form of embodiment herein disclosed, for it is susceptible of embodiment in various forms all coming within the scope of the claims which follow.

5 What I claim is:—

1. A safety-lock comprising a sheath section having an upper lap and an under lap connected together at one end, a spring locking element biased toward said upper lap, said upper lap and said under lap having adjacent surfaces which substantially contact each other except for an open central portion thereof wherein the upwardly biased 10 spring locking element normally extends, said open central portion comprising a raised surface of one of said laps, and a blade element adapted to enter within said open central portion of said sheath section and having a locking lip spaced intermediate the ends of said blade element and extending below the surface of the blade element, said locking lip being adapted to be engaged by said spring locking element whereby removal 20 of the blade element is prevented.

2. A safety-lock comprising a sheath section having an upper lap and an under lap connected together at a rear end, said sheath section having an opening at the end opposite to said rear end, a spring locking element extending from said under lap toward said rear end and being biased upwardly, and a blade element adapted to enter between said upper lap and lower lap at the opening 30 of said sheath section and having a locking lip adapted to be engaged by said spring locking element of said sheath section, said blade element having shoulders extending laterally from its longitudinal edges and 35 spaced from the locking lip longitudinally of the blade element a distance substantially equal to the distance of the rear locking end of said spring locking element from said opening.

4. A safety-lock comprising a sheath section having an upper lap and an under lap connected together at one edge, an open portion intermediate said two laps and communicating with an entrance close to another 45 edge of said sheath member, means for maintaining the surfaces of said upper lap and lower lap in substantial contacting relation near to the other two edges of said sheath section, a blade element adapted to enter at said entrance and to fit within said open portion, a lip extending from the surface of said blade element, said lip being raised from the material of the blade element whereby 50 a hole remains just forward of the lip, and a locking element extending from one of said laps and normally extending into said open portion whereby said lip may be engaged by said locking element when said blade element is introduced into the sheath 55 section and cause said locking element to fur-

ther enter said hole when an attempt is made to withdraw the blade element from the sheath member.

4. A safety-lock comprising a sheath section having an upper lap and an under lap, 70 said upper lap having a raised portion extending away from said under lap and forming a clear space, said under lap having a spring locking element biased toward said clear space, means for maintaining the contacting surfaces of said upper lap and said lower lap in contacting relation, means extending over the under surfaces of said under lap and of a portion of said spring locking 75 element for preventing said spring locking element from being displaced below the under surface of said under lap, and a blade element adapted to enter within said clear space, said blade element having a lip adapted to be engaged by said locking element 80 whereby removal of the blade element is prevented.

In testimony whereof I hereto affix my signature.
